UNITED STATES PATENT OFFICE

91,295

DESIGN FOR A BOTTLE

Arthur H. Dolge, Westport, Conn.

Application August 23, 1932. Serial No. 44,674

Term of patent 14 years

To all whom it may concern:

Be it known that I, ARTHUR H. DOLGE, a citizen of the United States, residing at Westport, in the county of Fairfield and State of Connecticut, have invented a new, original, and ornamental Design for Bottles, of which the following is a specification.

Reference being had to the accompanying drawing, forming part thereof.

Figure 2 is an elevation of another face of my novel bottle, showing my new design, the opposite face being substantially identical.

I claim:—

The ornamental design for a bottle, as shown and described.

ARTHUR H. DOLGE.
